UNITED STATES PATENT OFFICE.

WILLIAM E. DOUBLEDAY, OF BAY RIDGE, NEW YORK, ASSIGNOR TO ELLEN M. DOUBLEDAY, OF SAME PLACE.

METHOD OF STICKING FUR TO FIBROUS GOODS.

SPECIFICATION forming part of Letters Patent No. 253,160, dated January 31, 1882.

Application filed November 9, 1881. (No model.)

To all whom it may concern:

Be it known that I, WILLIAM E. DOUBLEDAY, a citizen of the United States of America, residing at Bay Ridge, in the county of Kings 5 and State of New York, have invented certain new and useful Improvements in Methods of Sticking Fur to Fibrous Goods; and I do hereby declare the following to be a full, clear, and exact description of the invention, such 10 as will enable others skilled in the art to which it appertains to make and use the same, reference being had to the accompanying drawings, and to letters or figures of reference marked thereon, which form a part of this 15 specification.

Figure 1 is a vertical section of a bat employed by me in carrying out my invention. Fig. 2 is a vertical section of the same bat placed upon a hat-body preparatory to the sticking 20 process. Fig. 3 is an elevation of a machine adapted for use in carrying out my invention.

As I propose in carrying out my invention to use well-known appliances which are commonly used in the art of manufacturing hats 25 and felted goods, I will give only a brief description of a felting-machine which is adapted for carrying out that part of my process which relates to sticking the fur to the woven or 30 felted fabric which forms the base of the material to be produced, such machine being shown and described in Patent No. 95,863, although I may employ any other machine of similar construction with such modification as I propose to make in this one.

Referring to Fig. 3, D' is the platen or jigger-plate, to which a rapidly-vibrating motion is imparted by means of cranks g, mounted on shaft B, the platen being elevated automatically through the medium of cam, (not shown,) 40 rock-shaft E², and levers E', to permit the feeding forward of the material which is being felted or hardened, this feeding being done by means of rollers j j', actuated by a cam and connecting devices.

In Fig. 1, A represents a conical bat formed 45 of fur, preferably nutria, formed by blowing the same upon a rotated perforated cone in substantially the manner commonly employed for that purpose. C is an outer layer of raw 50 cotton which has been blown upon the bat of

fur by the same machinery. In forming this cone I prefer to spread the fur in a thin layer upon a feeding-apron, and place upon the same apron, but in rear of the fur, a thin layer of cotton, so that the cotton will be deposited 55 upon the outer surface of the fur by the automatic operation of the machine. After the bat has thus been formed I remove it from the perforated cone, either in the condition in which it is formed or by wrapping it with a wet 60 cloth and then removing the bat and cloth together. This cone is of substantially the same taper and size as the hat-body to which it is to be applied, except that the cone is made as much longer than the body as is necessary 65 to permit the lower edge of the fur and cotton bat to be turned inward over the edge of the hat-body F to form a fur-lined brim of the hat, as is indicated in Fig. 2, and after the body has been placed within the bat and the edge 70 of the bat turned over within the lower edge of the body the two are flattened out, so that the two cotton surfaces of the brim come in contact with each other, as do the inner surfaces of the hat-body between the brim and the apex of 75 the triangular-shaped compound material thus shown; or, when preferred, a sheet of thin oiled paper or other suitable material—such as cotton cloth—may be placed between the adjacent surfaces of the cotton on the brim. 80

It will of course be understood that the extreme edge of the bat is of greater diameter than that portion of the hat-body which is adjacent to it after the bat has been turned inward, as indicated in Fig. 3, and that consequently the portion of the bat will be wrinkled or laid in folds when the article has been flattened out, with its inner portions in contact with each other, which is not, however, a serious objection, as will be explained. I now place 85 a number of these bats and bodies between the bed-plate and platen of the hardener, Fig. 3, and subject the same to the rapid vibratory motion of the platen, accompanied by heat or otherwise, as circumstances shall indicate, and, 90 when preferred, I place sheets of paper, cloth, or other suitable material between the hat and the bed-plate and platen of the machine. After this vibratory motion has been continued for a short time, dependent upon circum- 95 100

stances and conditions of temperature and moisture, the fur will be found to be stuck to the body of the hat, after which the hat is subjected to the usual scalding process.

- 5 It will be found upon completing the scalding operation that the surplus of fur which was produced by the wrinkling or folding above mentioned will come away when the layer of cotton is removed, leaving the hat-body thoroughly covered with firmly-attached fur; or, when desired, the operation may be varied by placing the hat-body within the conical bat of fur and cotton, and then cutting off or otherwise separating that portion of the bat of fur 10 and cotton which projects beyond the open end of the hat-body, thus forming a ring or band which may be used for covering the under brim of the hat with fur, such operation being performed separately—that is to say, in such case 15 20 I stick the fur to the outer face of the hat-body, and afterward turn the hat wrong side out, place upon its outer face the ring or band of fur and cotton, and stick it separately, having found by experience that in such operation 25 the fur can be made to adhere to and cover perfectly the lower edge of the hat in as satisfactory a manner as such lower edge can be covered by turning the bat over the edge of the hat-body, as I have first described, and 30 35 40 45 50 may be able to produce results which are in some respects more satisfactory than those I can produce by the first-described operation, owing to the fact that when carrying out such first-described method the material which is acted upon by the platen or jigger is not of uniform thickness, it being much thicker at the point occupied by the under brim than at the other portions of the hat, as will be readily understood by an examination of Fig. 2. While I employ a well-known machine—say that represented in Fig. 3—in sticking the fur to the felt or other fabric, of which the hat-body is composed, yet this operation is not at all analogous in many respects to the operation of hardening or felting, for which such machines are usually employed. In the ordinary use of these machines the platen rests with its entire weight upon a comparatively loose mass of fur, wool, or mixed fibers, and operates to unite them firmly and throughout their entire lengths into a firm, hard, compact

material called "felt," of much less thickness, when completed, than is the bat when the felting operation is commenced; but in carrying out my invention I so manipulate the machine 55 that only one end of each of the fibers or filaments of which the fur is composed is attached to the hat-body, leaving the rest of the fibers in a light, loose, "flowing" condition, substantially like that in which the fur exists upon the 60 animal from which it is taken.

In carrying out my invention either a very light platen must be used with a short period of vibration, or else the machine must be so constructed that the platen cannot rest with 65 its full weight upon the material; otherwise, instead of sticking the fur to the body of the hat, it (the fur) will be felted not only to the body of the hat, but the filaments of the fur will be felted to each other, so that they will 70 not flow, and thereby the end sought to be attained by my invention will be entirely frustrated.

I do not in this patent claim anything shown in patent to Hine, May 19, 1868, nor anything 75 relating to the scalding or sticking of fur by means of rollers, nor any other invention except that which is set forth specifically in the claim hereof, preferring to claim all other patentable features in another application which 80 I have filed as a division of this case. Hence I do not claim the process of felting nor any of the machinery employed therein; but

What I do claim is—

The herein-described improvement in the art 85 of making hats which have a flowing nap of fur, the same consisting in applying a bat of fur to a hat-body which has previously been felted and shrunk to the size and density which it is desired that it shall have when the hat is 90 completed, next subjecting the fur bat and body to the combined rubbing and pressing action of a vibrating plate, whereby the fur is stuck to the surface of the previously-felted hat-body, and subsequently scalding the same, 95 substantially as set forth.

In testimony whereof I affix my signature in presence of two witnesses.

WILLIAM E. DOUBLEDAY.
